US00D865684S

(12) **United States Design Patent** (10) Patent No.: **US D865,684 S**
 Gage et al. (45) Date of Patent: ** *Nov. 5, 2019

(54) **KEYPAD**

- (71) Applicant: **Lutron Technology Company LLC**,
 Coopersburg, PA (US)
- (72) Inventors: **Alexander Wade Gage**, Havertown, PA
 (US); **Elliot G. Jacoby**, Glenside, PA
 (US); **Jason C. Killo**, Emmaus, PA
 (US); **Brad Michael Kreschollek**,
 Bethlehem, PA (US); **Daniel Curtis**
 Raneri, Bethlehem, PA (US)
- (73) Assignee: **Lutron Technology Company LLC**,
 Coopersburg, PA (US)

(*) Notice: This patent is subject to a terminal disclaimer.

(**) Term: **15 Years**

(21) Appl. No.: **29/646,341**

(22) Filed: **May 3, 2018**

Related U.S. Application Data

- (63) Continuation of application No. 29/590,841, filed on Jan. 13, 2017, now Pat. No. Des. 821,336, which is a continuation of application No. 29/536,810, filed on Aug. 19, 2015, now Pat. No. Des. 780,702.

(57) **CLAIM**

The ornamental design for a keypad, as shown and described.

DESCRIPTION

FIG. 1 is a front perspective view of a keypad showing our new design;

FIG. 2 is a front view thereof;

FIG. 3 is a left side view thereof;

FIG. 4 is a right side view thereof;

FIG. 5 is a top view thereof; and,

FIG. 6 is a bottom view thereof.

The dashed broken lines represent structure or features which form no part of the claimed design; the broken lines themselves form no part of the claimed design.
